RAIL PULLER

Lauri O. Hyvari, Orr, Minn.

Application January 9, 1951, Serial No. 205,209

2 Claims. (Cl. 254—43)

1

This invention relates to devices used on railroads particularly by a repair crew and where rails have separated at the joints, and in particular this invention relates to a ratchet actuated clamp device having rail gripping elements carried by pivotally mounting levers with the rail gripping elements positioned to be placed over the heads of rails on opposite sides of a joint and with extended ends of the levers positioned to be drawn together by a ratchet for forcing the ends of the rails into engagement.

The purpose of this invention is to provide a manually actuated device for drawing ends of rails together that may be applied to rails without bolts, or other positive attaching means and that may readily be removed and carried from one position to another.

Various devices have been provided for drawing ends of rails together particularly with levers clamped to the rails but devices of this type used heretofore are not only troublesome and difficult to mount on the rails but require excessive force to operate. With this thought in mind this invention contemplates a ratchet actuated clamping device that can be set up in a comparatively few minutes and that multiplies the force applied to the gripping elements so that considerable force is applied to the rails with comparatively little effort.

The object of this invention is, therefore, to provide means for constructing a lever actuated device for drawing ends of rails together whereby the device may readily be positioned upon meeting ends of rails and operated without positive connections to the rails.

Another object of the invention is to provide a device for drawing ends of rails together which may readily be carried from one position to another.

A further object of the invention is to provide a manually actuated device for drawing ends of rails together which is of a simple and economical construction.

With these and other objects and advantages in view the invention embodies a pair of levers pivotally mounted on a connecting frame with U-shape gripping elements pivotally connected to and extended from sides of the levers and with the free ends of the levers connected by a manually actuated ratchet whereby with the gripping elements positioned over the heads of rails the rails are drawn together by actuating the ratchet.

Other features and advantages of the invention will appear from the following description taken in connection with the drawings wherein:

2

Figure 1 is a plan view of the improved rail puller illustrating the parts in operative positions and positioned upon adjoining ends of rails.

Figure 2 is a side elevational view showing the device with the parts in the positions shown in Figure 1.

Figure 3 is an end elevational view also showing the rail puller with the parts in the positions as illustrated in Figure 1, and with the angle on the near side of the follower removed.

Figure 4 is a longitudinal section through one of the levers of the rail puller being taken on line 4—4 of Figure 1.

Figure 5 is a cross section taken on line 5—5 of Figure 1 showing the frame to which the levers are pivotally connected.

Figure 6 is a sectional plan taken on line 6—6 of Figure 3 showing the ratchet pawl mounting parts.

20 Referring now to the drawings wherein like reference characters denote corresponding parts the improved rail puller of this invention includes levers 10 and 11, rail gripping jaws 12 and 13, a U-shape mounting frame 14, in which the levers 25 are pivotally mounted by pins 15 and 16, a ratchet bar 17 pivotally connected to the extended ends of the levers, an actuating pawl 18, a locking pawl 19, a ratchet handle 20, a support 21, and a spring 22.

30 The levers 10 and 11 are shown as illustrated in Figures 1 and 4 with the inner ends thereof pivotally mounted by the pins 15 and 16 between an upper arm 23 and the lower arm 24 of the frame 14.

35 The lever 10 is provided with a bracket 25, the inner end of which is mounted on the pin 15 through a flange 26 that is positioned below the head 27 of the pin and the outer end of the bracket is provided with a flange 28 through

40 which the end of the bracket is secured to the lever by screws 29. The flange 26 is also provided with locating grooves 30 and 31. The lever 11 is also provided with a bracket 32, similar to the bracket 25 and a flange 33 on the inner end is positioned under the head 34 of the pin 16. A flange 35 on the outer end is also secured to the lever by screws 36.

45 The gripping jaws 12 and 13 are of U-shape in cross section, as shown in Figures 1 and 2 and the jaw 12 is provided with a hub 37 by which it is pivotally connected to the outer end of a link 38 by a pin 39. The inner end of the link is pivotally connected to the lever 10 by a pin 40 which extends through the ratchet 25 and lever.

The jaw 13 is provided with a similar hub 41 through which the jaw is pivotally connected to a link 42 by a pin 43 and the inner end of the link 42 is pivotally connected to the lever 11 by a pin 44 which extends through the bracket 32 and also through the lever, as shown in Figure 4.

The pins connecting the levers, jaws and mounting elements are provided with cotter pins 45.

The frame 14 is provided with a handle 46, the ends of which are secured to the upper arm 23 of the frame by screws 47 and 48.

The levers 10 and 11 are resiliently urged apart by the spring 22, one end of which bears against the inner surface of the lever 11, and the opposite end of which is held in an opening 49 in the lever 10. The spring is provided with a coil 50 that is positioned against the inner surface of the lever 10, as shown in Figure 1.

The ratchet bar 17 is provided with a pin 51 which extends through an opening 52 in the outer end of the lever 11 and, as illustrated in Figures 1 and 4, a washer 53 on the pin 51 is positioned between the bar 17 and upper surface of the lever.

The ratchet bar 17 extends through a follower 54 that is pivotally mounted in an opening 55 in the outer end of the lever 10 by a pin 56 and, as illustrated in Figure 6, clip angles 57 and 58, secured to the base of the follower 54 by screws 59 and 60 provide mounting means for the actuating and locking pawls 18 and 19. The pawl 18 is pivotally mounted on a pin 61 and the pawl or dog 19 is pivotally mounted on a pin 62, the pins being mounted in the vertically disposed legs of the clip angles 57 and 58.

A socket 63, which is connected to the pawl 18 by a pin 64 extends upwardly and is positioned to receive the handle 20, as shown in Figure 3.

The pin 56 by which the follower 54 is pivotally connected to the end of a lever 10, also extends through a plate 65 forming the upper end of the U-shape support 21 and vertically disposed sections of the support are provided with flanges 66 and 67 which rest upon railroad ties 68.

With the parts arranged in this manner the rail gripping jaws 12 and 13 are positioned over the heads of rails, as indicated by the numerals 69 and 70 and as the pawl is actuated by the handle 20 the ratchet bar 17 is drawn through the follower so that the ends of the levers are drawn together and with the jaws 12 and 13 firmly gripping the rails the ends of the rails are, consequently, drawn into meeting relation.

The parts of the rail puller of this invention are of comparatively light weight so that the device may readily be carried by the handle 46.

After the ends of rails are drawn together by the rail puller the rails are secured by fish plates and after the rails are bolted together the ratchet is released by tapping the upper end 65 of the dog or pawl 19.

It will be understood that modifications may be made in the design and arrangement of the parts without departing from the spirit of the invention.

What is claimed is:

1. In a railroad rail puller, the combination which comprises a mounting frame, a pair of levers pivotally mounted through one of the ends thereof to the said mounting frame, links pivotally connected to the said levers and extended from the sides thereof, a reinforcing bracket for each lever, one end of each bracket being secured to its respective lever and each bracket extending toward the pivotally mounted end of each lever to be connected by the pivot to the lever and the pivot of the link with its respective lever extending through the respective bracket, inverted U-shape rail gripping jaws pivotally attached to the extended ends of the links, a ratchet bar extended across the extended ends of the levers with one end of the bar pivotally connected to one of the said levers, a follower pivotally connected to the extended end of the other lever and positioned with the ratchet bar extended therethrough, ratchet actuating pawls pivotally mounted in said follower and positioned to engage teeth of the ratchet bar, and a support positioned under the extended ends of one of the said levers.

2. In a railroad rail puller, the combination which comprises a mounting frame, a pair of levers pivotally mounted through one of the ends thereof to the said mounting frame, links pivotally connected to the said levers and extended from the sides thereof, inverted U-shape rail gripping jaws pivotally attached to the extended ends of the links, a ratchet bar extended across the extended ends of the levers with one end of the bar pivotally connected to one of the said levers, a follower pivotally connected to the extended end of the other lever and positioned with the ratchet bar extended therethrough, ratchet actuating pawls pivotally mounted in said follower and positioned to engage teeth of the ratchet bar, a spring pivotally attached to one of the said levers and positioned to engage the other lever for resiliently urging the levers apart, and a support positioned under the extended end of one of the said levers.

LAURI O. HYVARI.
